UNITED STATES PATENT OFFICE.

CHARLES E. WALSH, OF CLEVELAND, OHIO.

STEAM TRAP.

Application filed January 15, 1921. Serial No. 437,442.

To all whom it may concern:

Be it known that I, CHARLES E. WALSH, a citizen of the United States, residing at Cleveland, in the county of Cuyahoga and State of Ohio, have invented certain new and useful Improvements in Steam Traps, of which the following is a specification.

This invention relates to steam traps, and more particularly to traps which are employed with the lines of vacuum, and pressure heating systems.

The primary object of the present invention is to provide a simple and reliable trap construction embodying an outlet valve through which water of condensation that may accumulate within the trap is periodically discharged automatically.

A further object of the invention is the provision of a trap of this character that is noiseless in operation, and that comprises comparatively few parts, making it economical to manufacture.

A further object of the invention is the provision of means for efficiently grinding the contact surfaces of the valve and valve-seat of the trap, to maintain a perfect valve function.

The improvement further provides for easy access to the interior, or to the working parts of the trap, thereby facilitating the assembling of the elements and reducing to a minimum the cost of repairs if the operating parts become damaged.

With these and other apparent objects and advantages in view, the invention consists in the construction, combination and arrangement of elements as hereinafter described and particularly set forth in the appended claims, reference being had to the accompanying drawings which are made part of the specification, similar reference characters being employed to designate corresponding parts.

In the said drawings Figure 1 is a central vertical section through the trap, showing the valve closed. Fig. 2 is an end view of a tail piece used in connection with the trap. Figs. 3 and 4 are fragmentary central vertical sections taken at right angles to each other, illustrating the means for grinding the valve and valve seat, and Fig. 5 is a view of a type of instrument used in connection with the grinding.

The present embodiment of my invention comprises a casing 1, having a side branch 2 extending therefrom above the bottom, said

branch being adapted for connection with a radiator outlet, not shown, by means of a tail-piece 2^a attached to said branch by a coupling 2^b.

The casing 1 is provided at its upper end with a suitable cover 3, which is shown as having an outwardly projecting flange 3^a adapted to engage the top of the casing 1, and being provided below said flange with a skirt 3^b having an external thread 3^c adapted to fit an internal thread 1^a in the top of the casing 1, and when assembled a sealing gasket 4 is preferably interposed between the flange 3^a and the top of the casing.

The bottom of the casing is provided with a neck 5, having its lower portion provided with a thread 5^a, for the reception of a pipe, which may be the return pipe of a vacuum, or pressure heating system.

Within the neck 5, above the thread 5^a is a valve-seat fitting 6 having a frusto-conical surface 6^a. A tubular valve stem 7 is adapted to seat on the surface 6^a and extends vertically in the casing, the said stem carrying a float 8. A post 9 is firmly attached, centrally, to a boss 3^c on the cover 3, and depends therefrom into the bore of the tubular stem 7, having a sliding fit therein and forming a vertical central guide for the valve. The post 9 has a shoulder 9^a on which is seated a ring 10, and a spring 10^a is mounted on the post between said ring 10 and the boss 3^c. The spring 10^a cushions the upward action of the valve and prevents "chattering" or renders the trap noiseless in its action.

The post 9 is provided with one or more annular grooves 9^b, within the bore of the stem, into which water of condensation, or sweat which forms on the post, seeps, and forms a water seal between the post and the valve stem 7. This is a salient feature of the improved construction, inasmuch as it accelerates the vacuum function.

In operation, the air and steam enters the casing through the connection 2. The water of condensation collects in the chamber 11 and causes the float 8 to rise, thereby lifting the valve stem 7 off the seat 6^a. The water is then discharged from the chamber 11 through the neck 5 into the return line pipe connected with said neck.

The stem 7 is provided with two diametrically disposed apertures 7^a which are contributory factors in means for maintaining efficiency in the valve function.

For carrying out this feature a key is provided, an embodiment of which is shown in Figs. 3, 4 and 5. A stock 12 has a squared stem 12^a which adapts it to be gripped by a brace, wrench, or other suitable operating tool. Spring arms 12^b are firmly attached to the stock 12, and extending therefrom are provided with fingers 12^c, which are adapted to engage the apertures 7^a in the stem 7, the arms 12^b being inserted through the neck 5 and the opening 6^b in the valve fitting 6, when the trap is fully assembled, but detached from the return pipe. The key being thus connected with the valve member 7, when rotated, causes the bearing surfaces of the valve members to conjointly grind, and thereby form an absolutely perfect, tight-fitting bearing for the valve and valve-seat, owing to the stem 7 being precisely centered by the post 9. This feature insures perfect action of the valve and prolongs the serviceable life of the trap.

The apertures 7^a may be tapped and plugs 7^b provided as closures therefor, or one or both of said apertures may be left open for the escape of air when steam is initially turned into the system, and also for the discharge of water which may be in the chamber 11 below the float 8 after steam has been cut off from the system, or from the part thereof with which the trap may be employed.

The bore 2^c of the tail-piece 2^a is preferably square in cross-section, to facilitate the connection of said tail-piece with the radiator by the insertion and rotation of a removable instrument in the bore.

Having thus described my invention, what I claim as new and desire to secure by Letters Patent, is:—

1. In a steam trap, the combination of a casing, and a closure cap in the top thereof, said casing having an inlet connection, and provided with a discharge connection in the bottom thereof, a valve-seat in the discharge element, a valve operative on said seat, said valve comprising a tubular stem having a float attached thereto a guide element fixed in the closure cap, depending therefrom and having a sliding fit in the bore of the tubular stem, apertures provided in the valve stem above the valve-seat, for engagement with a key adapted for insertion through the outlet, whereby said valve may be rotated on the valve-seat.

2. In a steam trap, the combination of a casing, and a closure cap in the top thereof, said casing having an inlet connection, and provided with a discharge connection in the bottom thereof, a valve-seat in the discharge connection, a valve operative on said seat, said valve comprising a tubular stem having a float attached thereto, a guide element fixed in the closure cap, depending therefrom and having a sliding fit in the bore of the tubular stem, apertures provided in the valve stem above the valve-seat, for engagement with a key adapted for insertion through the outlet, whereby said valve may be rotated on the valve-seat, means for closing said apertures after the key has been removed.

In testimony whereof I affix my signature.
CHARLES E. WALSH.
